LIGHTING FIXTURE OR SIMILAR ARTICLE

Werner W. Schwartz, Jackson Heights, N.Y., assignor to Consolidated Sewing Machine Corp., New York, N.Y., a corporation of New York

Filed Feb. 14, 1968, Ser. No. 10,576

Term of patent 14 years

(Cl. D48—20)

FIG. 1 is a side elevational view of the lighting fixture or similar article, embodying my new design, with the lamp head in its normal position;

FIG. 2 is an enlarged side elevational view thereof with a portion of the stem broken away and the lamp head in a level position;

FIG. 3 is an enlarged front elevational view of the lighting fixture or similar article with the lamp head in the position of FIG. 2;

FIG. 4 is an enlarged rear elevational view thereof; and

FIG. 5 is a perspective view of the lighting fixture or similar article with a portion of the stem broken away.

The support member in FIGS. 2-5 has been broken away for convenience of illustration.

I claim:

The ornamental design for a lighting fixture or similar article, substantially as shown.
